UNITED STATES PATENT OFFICE

GEORGE VOLTZ, OF ROCHESTER, NEW YORK, ASSIGNOR TO BASTIAN BROTHERS COMPANY, OF ROCHESTER, NEW YORK, A CORPORATION OF NEW YORK

BILL FOLD

Application filed June 24, 1929. Serial No. 373,075.

The present invention relates to bill folds and an object thereof is to provide a construction having a pocket which will not be apparent upon a casual inspection of the bill fold and can serve to conceal money, papers, or the like from persons unfamiliar with its construction.

To this and other ends, the invention consists of certain parts and combinations of parts all of which will be hereinafter described: the novel features being pointed out in the appended claims.

In the drawings:

Fig. 1 is a view of the inner face of the bill fold in open position;

Fig. 2 is a section on the line 2—2, Fig. 1 showing the outer pocket flap open;

Fig. 3 is a similar view showing the inner flap in open position and the outer flap closed.

In the illustrated embodiment of the invention, 1 indicates the main or body layer of the bill fold, this layer being foldable preferably along one side of a transverse median line. In this instance, on one side of this median line is arranged a short layer or wall 2 which is stitched or otherwise secured at three edges at 3, its fourth edge being free. Between the layers 1 and 2 is an intermediate wall 4 held by the stitches 3 and extending to the free edge of the wall 2. A second intermediate wall 5 is preferably also secured by the stitchings 3 between the wall or layer 4 and the wall or layer 1. This wall 5 has its free edge below or spaced from the free edge of the wall 4 so that its upper or free edge will be hidden. It will thus be seen that the three walls 2, 4 and 5 form three pockets 6, 7, and 8 on one side of the wall 1, the upper ends of the pockets 7 and 8 merging into one chamber at their upper ends.

With the purpose in view of closing the pocket 6, the wall 4 carries an extension flap formed, in this instance, of a liner portion 9 in one piece with the wall 4 and a finishing layer 10 of heavier material, such as leather.

With the end in view of still further hiding the pocket 7, another flap extension 11 is carried by the wall or layer 4 and projects rearwardly from said wall and into the pocket 8 over the upper edge of the wall 4. This flap has the tendency to create the impression that it forms the inner face of the wall 4, and also to the fact that the pocket 8 is open to access. In this instance, the flap or extension 11 is in one piece with the outer layer 10 of the flap which closes the pocket 6.

A snap fastener 12 may secure the outer flap to the wall 2.

From the foregoing it will be seen that there has been provided a bill fold in which three pockets are arranged one behind another, the wall separating the second pocket from the first or outer, carrying two flaps projecting from opposite sides thereof and acting as closures for the first and second pockets, the flap closing the second pocket serving to hide or conceal the second pocket and to concentrate the observer's attention on the third pocket.

What I claim as my invention and desire to secure by Letters Patent is:

1. A bill fold comprising three pockets arranged one behind the other and having two walls separating them, and two flaps carried by the wall separating the first from the second pocket, one of said flaps closing the first pocket and the other closing the second pocket and extending into the third pocket.

2. A bill fold comprising three pockets arranged one behind the other and having two walls separating them, and two flaps carried by the wall separating the first from the second pocket, one of said flaps closing the first pocket and the other closing the second pocket and extending into the third pocket, the two flaps having a common layer which is the outer layer of the flap closing the first pocket.

3. A bill fold comprising three pockets arranged one behind the other and having two walls separating them, and two flaps carried

by the wall separating the first from the second pocket, one of said flaps closing the first pocket and the other closing the second pocket and extending into the third pocket, the two flaps having a common layer which is the outer layer of the flap closing the first pocket, and the wall carrying the two flaps being formed in one piece with a portion forming the inner layer of the flap closing the outer 10 or first pocket.

GEORGE VOLTZ.
